UNITED STATES PATENT OFFICE.

WILLIAM C. FORD, OF LAWRENCE, MASSACHUSETTS.

SHOE-BLACKING MACHINE.

No. 902,390.

Specification of Letters Patent.

Patented Oct. 27, 1908.

Application filed July 15, 1907. Serial No. 383,765.

To all whom it may concern:

Be it known that I, WILLIAM C. FORD, a citizen of the United States, residing at Lawrence, in the county of Essex and State of 5 Massachusetts, have invented certain new and useful Improvements in Shoe-Blacking Machines, of which the following is a specification.

This invention relates to improvements in 10 shoe-blacking machines, and the object is to provide a simple and effective machine which may be conveniently operated by the user to apply the blacking and to impart a polish to the shoe.

15 With the above object in view, the invention consists in the novel features of construction hereinafter fully described, particularly pointed out in the claims, and clearly illustrated by the accompanying drawing, in 20 which

Figure 1, is a view, partly in elevation and partly in section, showing a shoe-blacking machine embodying my invention; Fig. 2, a vertical sectional view.

25 Referring now more particularly to the drawings, 1 designates the base of the machine having a compartment 2 formed therein with an opening at one end thereof and containing the spraying device for the shoe 30 blacking hereinafter described. Raised from the base 1 is a support 3 having a forked upper end, the forks 4 of which are provided intermediately of their ends with bearings for a crank-shaft 5, the crank 6 of which is disposed between the two forks. Said shaft 35 carries the two spaced rotary brushes 7 having the bristles thereof facing each other and disposed a sufficient distance apart to operate upon the shoes to be polished. The bristles, as shown in Fig. 2, gradually increase in 40 length from the inner portion of the brush to the outer periphery thereof, so that the top of the shoe, as well as the sides, will be polished.

45 As shown in Fig. 1, the brushes have a portion of the bristles omitted so as to permit ready access by the foot to the pedal and removal therefrom, and to avoid the possibility of any of the bristles being caught between 50 the foot and the pedal. The forks 4 of the support at their upper ends carry suitable

bearings for a pedal 8, which is shaped to receive the foot of the user. The forward end of said pedal is operatively connected with the crank of shaft 5 by a connecting rod 9, so 55 that by rocking the pedal the crank shaft is operated to revolve the two brushes.

In order to protect the trousers and hose of the user, where low shoes are worn, I provide a shield 10 which is adjustably supported by 60 the forward end of the pedal by means of a rearwardly-curved arm 11, which is adjustable in a sleeve or collar 12 formed on the pedal and held in its adjustment by a screw 13.

65 The compartment 2 of the base is provided with a reservoir 14, for liquid blacking, which is placed therein through an inlet opening 15. In the form of spraying apparatus illustrated in Fig. 1, a bellows 16 is 70 provided to be operated by the foot of the user, which is inserted in said compartment through its open end. An air tube 17 connects this bellows with the blacking reservoir and is provided with a suitable valve 18' for 75 preventing the inlet of blacking thereinto. Extending from this blacking reservoir is a spraying tube 18 having perforations through which the blacking is ejected, said tube being 80 arranged in proper position to distribute the blacking over the shoe.

85 From the above description, it will be seen that I have provided an exceedingly simple device for spraying the blacking and for imparting a polish to the shoe. The operation of this spraying device and the machine is entirely by the foot of the user, so that it is not necessary to bend over at all, whereby the operations may be performed in a very 90 convenient manner.

Having thus fully described my invention, what I claim as new, and desire to secure by Letters Patent of the United States, is:—

95 1. In a shoe blacking machine, a crank shaft, rotary brushes carried thereby, an intermediately pivoted foot rest disposed between the faces of the brushes, and an operative connection between said foot rest and the crank shaft.

100 2. In a shoe-blacking machine, a shaft having an intermediate crank, brushes carried by said shaft on opposite sides of said

crank and having their bristles facing each other, an intermediately pivoted foot rest disposed between the bristle portions of said brushes, a connecting rod operatively connecting said foot rest and the crank of said shaft.

3. In a shoe-blacking machine, a rotary brush, a foot rest, an operative connection between said foot rest and the rotary brush

whereby the movement of the former imparts movement to the latter, and an adjustable shield carried by said foot rest.

In testimony whereof I affix my signature, in presence of two witnesses.

WILLIAM C. FORD.
